UNITED STATES PATENT OFFICE.

WILBUR R. BIRNEY, OF DAYTON, OHIO.

CHECK-PRINTING MACHINE.

1,263,024.

Specification of Letters Patent. Patented Apr. 16, 1918.

Application filed July 8, 1912. Serial No. 708,158.

To all whom it may concern:

Be it known that I, WILBUR R. BIRNEY, a citizen of the United States, residing at Dayton, in the county of Montgomery and State of Ohio, have invented a new and useful Check-Printing Machine, of which the following is a specification.

Although designated a check-printing machine, my invention is related in a general way to type-writing machines; it might, in fact, be called a typewriter. Moreover, with some modification it would make a very excellent typewriter, which would have at least two unique and valuable features; viz., quietness and the possibility of correcting an error before it is printed.

The embodiment of my invention illustrated and described in this application, is designed for the purpose of printing checks and the like, and one of its objects is to save time. Another object is to render the date of the check, name of payee and the amount for which the check is made, indelible. A further object is to insure that nothing can be added to what has been printed on the check by the machine without the fact that something has been added being quite obvious.

In addition to printing a check my machine prints a duplicate of the matter printed on the check, upon a record sheet. This sheet is made broad enough to accommodate several columns of duplicates, and by shifting the paper each duplicate may be placed in any desired column. By this means each column may be reserved for checks of a certain class; *e. g.*, each of two or more columns may be used for checks drawn against certain accounts. Obviously, there are many ways in which segregation of the duplicates may be found useful.

The check printing and duplicate printing devices are entirely separate, and the latter is automatic in its action. Each may be rendered inaccessible to a person having access to the other; *e. g.*, the record sheet and all mechanism connected with it may be inclosed under lock and key, while fully operable by a person who has no means of gaining access to it. Such person would be able to shift the record sheet so as to print duplicates in the desired column, but would otherwise have no control over the record,

nor could he prevent the record being made. On the other hand, by locking the operating handle of the machine even the person who has access to the record could be prevented from operating the machine or adding anything to the record.

A brief description of the machine will help one to understand the detailed description which is to follow:

A blank check is placed in a holder and by the holder is clamped to the platen; the platen is then rolled forward until it comes to a stop. The keys are now operated as in a typewriter. There is this difference, however, in the action produced when the keys are operated: First,—after each key is operated the key board moves to the right a short distance. Second,—operating the keys does not print anything on the check; it merely sets certain mechanism in the machine.

The key board is what is known as "standard" (see Fig. 4) and unless the key in the lower left hand corner, marked "Fig." is first pressed, the effect of pressing a key will be to cause the letter which appears on the key to be printed on the check later. The keys of the upper row have both letters and numerals: using these keys before the Fig. key has been pressed will set the machine to print letters; after the Fig. key has been pressed, they will set it to print numerals. Pressing either of the keys in the lower row having two characters on them, after the Fig. key has been pressed, causes the proper character to appear on the check. Keys must be operated for all that is to appear in a single line before the operating handle is moved; if the line contains letters and numerals, the letters must be set first.

Having set up a line, the operating handle at the right of the machine is pulled toward the operator as far as it will move and then returned to its normal position. The top line has now been printed on the check, the platen has been shifted, carrying the check with it into position to receive the second line, and the key board has been returned to its left hand or normal position. The keys are now operated and all of the second line set up, after which the operating handle is moved as before. In like manner the third line is set up and printed. Simultaneously

with printing each line, an exact duplicate of the matter it contains is printed on the record sheet. When a check is finished a small lever is lifted to permit the platen to be rolled toward the operator, after which the printed check is removed from the holder.

Figure 1 is an elevation at the right hand end of my machine with the end frame, operating lever and handle removed.

Fig. 2 is a front elevation, with operating handle removed.

Fig. 3 is a plan view of the machine, with the operating handle removed.

Fig. 4 is a plan of the key conveyer and a portion of the mechanism for returning it to a normal position.

Figs. 5 and 6 are details of parts of the conveyer returning mechanism.

Fig. 7 is detail of a duplicate printer shifting mechanism.

Figs. 8 to 14 are details of the conveyer moving mechanism and the mechanism for returning the conveyer to its normal position.

Figs. 15 to 18 are details of the propeller and associated mechanism.

Figs. 19 and 20 are details of the key mechanism.

Figs. 21 and 22 are details of the platen.

Figs. 23 to 26 inclusive are details of the mechanism for moving the type sectors and the mechanism for stopping them.

Fig. 27 is a plan of the stop carriage and parts of its controlling mechanism.

Fig. 28 is a view of the parts shown in Fig. 27 when in a different position.

Figs. 29 and 30 are details of mechanism related to the parts shown in Figs. 27 and 28.

Figs. 31 and 32 are side elevations, showing the action of the type segments.

Fig. 33 is a section on line 33, Fig. 3.

Figs. 34 to 41 are details of the mechanism for actuating the platen.

Fig. 42 is a view of the mechanism for restoring the stops to their normal position.

Figs. 43 to 45 are details of the mechanism shown in Fig. 42.

Figs. 46 and 47 are details of the inking mechanism.

Figs. 48 and 49 are details of the mechanism for adjusting the lateral position of the printing sectors.

Fig. 50 is an enlarged view of the face of a portion of a printing sector showing the serrations in the face of the type.

Fig. 51 is a fragmentary, sectional view through the platen and a type, to demonstrate the position of the serrations on one with reference to the other.

Fig. 52 is a section through the machine on a line 52, Fig. 3.

Figs. 53 and 54 show the manner of locking the operating handle.

Figs. 55 and 56 are front and end eleva-

tions respectively of a machine in which the duplicate printing mechanism is inclosed and accessible only to one who has a key.

Similar numerals refer to similar parts throughout the several views.

70

25 is the base plate of my machine, upon which is mounted end frames 26 and 27, which in turn are tied together by tie bars 28, across the top of the machine, and a back plate 29. (See Fig. 2.) A rail 30 projecting upward from the base, and a rod 31 carried by the side frames, act as guides upon which the key conveyer runs. (See Fig. 1.)

75

35 represents the main frame of the key conveyer, the front portion of which is supported by grooved rollers 36. A single plain roller 37, attached to the frame 35, rolls upon the track 30. The rear portion of the conveyer is prevented from jumping up by a guard rail 38, which is attached to the base 25. Shaft 39 is mounted in the ends of the frame 35 and upon this shaft the keys 40 are mounted and rock. A plate 41, having a slot for each key, is secured to the front of the frame 35 and keeps the keys in proper lateral position. A rock shaft 42 is mounted in the ends of the frame 35 below the keys, upon which shaft are rigidly secured arms 43 and 44. (See Figs. 4, 8, 9, 10, 11.) The forward ends of these arms are tied together by rod 45. A spring 46 tends to rock the shaft 42 and press the rod 45 against the lower edges of the keys and move them to the upper ends of the slots 40 in plate 41. When a key is pressed down the remaining keys are held in their elevated positions by means which will presently be explained.

90

A bell-crank, comprising arms 50 and 51, is pivotally mounted at 52 upon the frame 35, and its movement about the pivotal point is limited by stops 53 and 54. (See Figs. 12 and 13.) A spring 55, whose other end is attached to the frame 35, tends to keep the arm 51 against the stop 53. A link 56 is pivotally attached to the end of arm 50, its lower end having a slot 57, through which the rod 45 passes. A pawl 58 is pivotally mounted on the lower end of arm 51 and engages teeth on a rack-bar 59 rigidly secured to the base 25, a spring 60 tending to keep it thus engaged. The pawl has a laterally extending tail 61 which, when a key is actuated, is engaged by an extension 62, forming part of the arm 43 and the pawl lifted out of engagement with the rack bar. The slot 57 in the link 56 (see Fig. 11) permits of sufficient movement of the rod 45, and hence of the arm 43, to disengage the pawl without rocking the bell-crank. Continued movement of the rod, however, causes it to engage the bottom of the slot 57 and rock the bell crank; the pawl moves with the arm 51, resulting finally in 115

120

125

130

the tail 61 passing from beneath the extension 62. The pawl is then free to drop into the next notch of the rack bar, as it is seen to have done in Fig. 13.

- 5 A lever 65 is attached by screw 66 to the end of frame 35, the screw passing through a slot 67 in the lever. A spring 68 serves the double purpose of tending to hold the lever down and throwing it to the right as 10 seen in Fig. 10. A pin 69 carried by the arm 43, engages a hump 70 on the edge of the lever 65 when a key is actuated and carries the lever forward, causing its lower end to enter a space between two teeth of 15 the rack-bar. This action is so timed that it is completed before the pawl 58 is disengaged from the rack.

Inspection of Fig. 13 reveals this condition: The bell-crank, fixed on a pivot attached to the frame 35, is being urged to rock on its pivot by the spring 55, whose left hand end, not shown, is also attached to the frame 35. Obviously, were the bell-crank permitted to respond to the influence 20 of the spring, the engagement of the pawl in the rack-bar preventing the lower end of the arm 51 moving, the rocking of the bell-crank would move the frame to the right until the arm 51 engaged the stop 53. In 25 practice, however, the lever 65 being engaged with the rack bar prevents the frame moving as the rod 45 starts to move upward. But, because of the slot 57, the rod 45 is permitted to rise a certain distance while 30 the bell-crank remains stationary, and during this initial movement of the rod, a pawl 71, carried by the arm 43, (the pawl having, under the influence of a spring 72, engaged a lug 73 on the lever 65) lifts the lever 65 35 out of engagement with the rack-bar, and being thereby released the frame 35 and all the parts carried by it are moved to the right. The tail of the pawl 71 engages a pin 74 in the frame 35 as the arm 43 moves 40 upward and rocks the pawl sufficiently to withdraw it from under the lug 73, thus permitting the lever 65 to resume the position it occupies in Figs. 10 and 11. The 45 amount of movement permitted the bell-crank by the stop 53 is such as to move the frame a distance equal to that from the center of one tooth in the rack-bar to the center of the next. Moreover, the initial movement of the rod 45 is sufficient to prevent the 50 extension 62 striking the tail 61 as the frame moves to the right. The pin 75 keeps the movements of the lever 65 within bounds. From the foregoing description it is clear 55 that the conveyer moves to the right a certain distance each time a key is actuated.

The rear member, 80, of the frame 35 has a succession of vertical holes, one hole being immediately above the end of each key 40, in each of which a tube 81 is secured 45 with set screw 82. (See Figs. 4, 19, 20.)

Above the member 80 and about midway the space occupied by the tubes a transverse segmental member 83 is supported by arms 84. (See also Figs. 23, 24.) A succession of radially disposed holes 85 are drilled in the 70 member 83, said holes being contracted at their upper ends. In each of these holes a plunger 86, having a head 87, is inserted, the head being of a size suitable to act as a guide for the plunger in the hole while 75 the shank of the plunger slides freely through the contracted portion at the upper part of the hole. A compression spring 88 is confined between the head of the plunger and the shoulder formed by the contraction 80 at the end of the hole. Each of the tubes 81, has a bushing 89 secured to its end, which bushing is secured in one of the holes 85. A wire 90 is inserted in each tube, the upper 85 end of which enters the hole drilled in the plunger 86. A terminal 91 is secured to the other end of each wire. The wires and tubes are so proportioned that when the plunger 86 touches the bushing 89 the extension 91 will protrude below the member 90 just far enough to touch the end of the key below it. When a key is actuated it pushes the terminal upward in the hole, moving the wire longitudinally in the tube and in turn pushing the plunger outward. 95

The strength of the spring 88 must be sufficient to move the wire in the opposite direction in the tube. When a key is depressed the remaining keys are deprived of the support afforded by the rod 45, but the 100 force remaining in the spring, plus the friction of the wire in the tube, is available to prevent the outer end of the key dropping down when the rod 45 is depressed by another key.

A stop carriage 97 (see Figs. 1, 27) is mounted to slide upon rods 95 and 96, which pass through and are carried by the end frames 26 and 27. This carriage is built up of a plurality of segmental plates 98, 110 each of which has a row of laterally extending lugs 99 (see Figs. 23, 24) along its inner edge and a row of similar lugs 100 along its outer edge. Plates 98 are tied together by bolts 101 and a rod 102. (See Fig. 42.) 115 The lugs 99 and 100 on each plate abut the next adjacent plate and act as spacers. The space between each two lugs 99 is in radial alignment with a space between two lugs 100 and in each pair of spaces a sliding 120 member 103, which I will hereinafter call a stop, is placed. Each stop has an enlarged central portion, in which is drilled a hole for housing a compression spring 104. The shoulders formed by the change between the 125 enlarged central portion of a stop and its smaller extremities engages the lugs 99 and 100 and limits the movement of the stop. The length of the lugs 99 and 100 is such as to permit the stops to move freely be- 130

tween the plates 98 after they are assembled. The compression spring 104 bearing against the plates 98 produces enough friction to hold the stop in whatever position it is placed.

Reference to Figs. 1 and 24 shows that the stop carriage is supported in close proximity to the member 83, which is carried by the conveyer with each plunger 86 in radial alignment with a stop 103. The normal position of the conveyer with reference to the stop carriage is such that should a key be actuated the plunger 86 associated with it would engage a stop in the first row or bank at the left of the carriage. As has already been explained, when the depressed key is released the conveyer moves to the right one step, which will bring the plungers 86 into operative position with reference to the stops of the second bank; and in like manner the conveyer moves to the right after the operation of each key, bringing the plungers 86 successively into operative position with reference to the several banks of stops.

A device, hereinafter called a propeller, is mounted to slide and rock upon a rod 110 carried by the side plates 26 and 27. The propeller comprises the tubular member (see Figs. 15, 16, 17, 18) 111 mounted on the rod 110, having an arm 112 rigidly secured to one end and an arm 113 rigidly secured to the other end, said arms being tied together by a rod 114. Extending forward from the arm 112 is an arm 115, normally lying in a slot 116 formed in the front member of the conveyer frame 35, by which the propeller is moved in unison with the conveyer. A rearwardly extending arm 117 has at its extremity a slot which embraces a rod 118. This rod is carried by levers 119 and 120, said levers being rigidly secured to a rock shaft 121 mounted to rock in the ends of the frame 35. (See Fig. 4). The lever 119 has an extension 122, which is engaged by the rear end of the key marked Fig. Figs. 17 and 18 show respectively the position of the propeller and lever 119 before and after the Fig. key has been actuated. In Fig. 17 the arm 115 is engaged in the slot 116 while the upper end of the lever 112 stands away from the plates 98. In Fig. 18 the arm 115 has been lifted out of the notch 116 while the end of the lever 112 has entered a space between the two plates 98. These arms, 112 and 115, may, considered collectively, be regarded as a single pawl which is capable of entering a recess between two plates 98 or the slot 116, and in some of the claims they will be referred to in that manner. After the Fig. key has been pressed the propeller remains stationary while the conveyer moves on as keys are actuated.

45 A shaft 125 is mounted to rotate in the

side frames 26 and 27 and a segmental pinion 126 is rigidly secured to the end of the shaft outside of the latter frame. (See Figs. 2, 3, 33). A segmental gear 127 mounted on a rock shaft 128, also journaled in side frames 26 and 27, meshes with the pinion; an operating handle 129 is rigidly secured to the projecting end of the shaft 128. The normal position of the operating handle is shown by dotted lines in Fig. 33. Upon the shaft 125 is mounted a tubular shaft 130, the latter being enough larger than the former to accommodate a succession of spiral springs 131. Figs. 23, 24 and 25 illustrate the construction of the shaft 130; it has a longitudinal groove 132, and a succession of transverse grooves 133, which, extending to the longitudinal groove, leaves a succession of free standing sections 134. The shaft 130 is rigidly secured to the shaft 125 by suitable bushings inserted at each end, through which the shaft 125 passes, with suitable pins to hold them in place.

A plurality of type segments 135 are mounted to rotate upon the shaft 130. Extending inwardly from each segment is a tongue 136, having at its inner end a hook on which the perforated end of a spring 131 is hooked. Each of the tongues passes through one of the slots 133. The inner ends of the springs are bent into a substantially radial position and lie in a slot 137 formed in the shaft 125. An extension 138 formed on each segment carries a lug 139. The segments are of two sorts: one has type representing letters and certain special characters such as "&" and a star; the other has numerals and certain special characters. In the present machine all of the segments having letters are arranged in a group to the left of the group containing all of the segments having numerals, the two groups being divided by a single blank segment.

In a bracket 150 carried by the side frame 126 a vertical shaft 151 is journaled, said shaft carrying at its upper end an arm 152 and at its lower end an arm 153, both of said arms being rigidly secured to the shaft. (See Figs. 2, 3, 27). A roller 154 carried by the arm 152 lies in the race of a cam 155, rigidly secured to the shaft 125. A block 156, mounted to slide on the rod 95, is connected by a slot and pin connection to the arm 153. When the Fig. key is actuated to throw the arm 112 into a space between two plates 98, the upper end of the arm 113 is moved into the path of the block 156. The race in the cam 155 is so formed that during the early portion of the rotation of the shaft 125 the arm 153, actuated by the roller 154, arm 152 and shaft 151, is moved from the position shown in Fig. 27 to that shown in Fig. 28, in which figure a portion of the arm 153 is shown. In moving to the posi-

tion shown in Fig. 28 the block 156 pushes the arm 113 ahead of it, thereby moving the propeller to the position it occupies in Fig. 28.

- 5 The parts shown in full lines in Fig. 27 are in their normal position, *i. e.*, in the positions they occupy at the beginning of an operation. The arm 115 shown in dotted lines in Fig. 27 is in its extreme right hand position and it has been brought to this position by the action of the keys. The notch 116 being one space to the right of the arm 115 shows that after the arm 115 reached the position shown in dotted lines Fig. key 15 has been pressed, which disengaged the arm 115 from the notch 116 and moved the conveyer one space to the right. At this particular stage in the operation it would perhaps be more appropriate to say that operating the Fig. key releases the conveyer, since the propeller, having come in contact with the collar 157 on the shaft 95, could not move farther. Therefore, in order to enable the conveyer to continue its movement it was necessary to press the Fig. key and disconnect the conveyer from the propeller. The position of the propeller shown in dotted lines in Fig. 27 being the same as the position of the propeller in Fig. 28, 25 it is clear that its total stroke, whether moved by the conveyer or by the cam 155, is the same length. It is also clear that should the propeller be moved by the conveyer to any point between the two extremes of its stroke, operation of the handle will, through the cam 155 and parts associated with it merely complete the stroke of the propeller, which was begun by the conveyer through the action of the keys. 30 The operation of the portion of the machine so far described will now be explained:
- Beginning with the parts in their normal positions, required keys are actuated. If the matter to be printed contains letters and numerals the keys must be actuated for the letters first and, after pressing the Fig. key, the keys are actuated as before, but the keys then actuated will cause numerals instead of letters to be brought into printing position when the handle is operated. Each time a key is actuated a stop 103 is pushed upward as is indicated in the case of one stop in Fig. 24. When the key is released the conveyer moving to the right brings the plungers 86 into operative position with reference to the next bank of stops; continued actuation of the keys brings plungers into operative position with reference to each bank of stops successively. In Fig. 23 it 55 will be seen that when a stop is raised by a key it is projected into the path of the lug 139 on a type segment. Having actuated the required keys the operating handle is moved toward the operator, thereby rotating the 60 shaft 125 which carries with it the type seg-

ments and the cam 155. The movement of the propeller is so timed that it reaches its extreme right hand position before the lugs 139 on the type segment arrive at a point where they could engage a stop 103, even 70 though the extreme right hand stop, as seen in Fig. 24, had been projected into the path of a sector. In no case can the operating handle be moved until the Fig. key has been pressed, because the conveyer being locked 75 to the rack-bar and the propeller locked to the conveyer frame will prevent the arm 153 moving. Suppose twenty letter keys were actuated: the propeller will have been moved to the right to a point where, should the Fig. 80 key be actuated, the arm 112 will enter the space between the twentieth and twenty-first plates 98, and when the propeller is moved to the position shown in Fig. 28 it will carry the stop carriage with it, but not so 85 far as the stop carriage has been moved in said figure. Instead, the stop carriage will be twenty spaces to the left of the position shown in Fig. 28. Should thirty letter keys have been pressed instead of twenty the carriage 90 will be thirty spaces to the left of the position shown in Fig. 28; from which it will be seen that the distance the carriage moved is inversely proportioned to the number of keys actuated before the Fig. key has 95 been pressed. In the case of Fig. 27, where the propeller has been moved the full limit of its stroke by the conveyer, the carriage will not be moved when the handle is operated.

100 The carriage having been moved by the propeller as explained, continued rotation of the shaft carries the segments past the carriage and whenever a lug 139 on a segment encounters a stop the movement of that 105 segment ceases, the spring 131 by which it has been driven permitting the segment to stop while the shaft continues to rotate. In this manner the characters required to print a line are brought into alignment with the 110 platen.

A bevel gear 160 rigidly attached to the shaft 125 meshes with a bevel pinion 161 carried by vertical shaft 162, (see Fig. 2) the lower end of which shaft is rigidly attached 115 to gear 163, meshing with a gear 164 mounted upon a stud 165 secured to the base 25. (See Figs. 4, 5.) An arm 166 is mounted and free to rotate upon the stud 165, the outer end of said arm being pivotally connected to a link 167. The other end of the link 167 is connected by a slot and pin connection to a block 168 mounted to slide on a rod 169 carried by the side frames 26 and 27. A spring 170 (see also Figs. 8, 9, 10, 11, 12, 125 14) tends to move the block with reference to the link 167 in a direction away from the end of the link to which it is attached. A lever 171 is attached to the gear 164 and has an upwardly extending lug 172, which, as 130

the gear rotates, is adapted to engage one side of the arm 166 and move it. The train, beginning with gear 160 and terminating with gear 164, is so timed that when the 5 shaft 125 has nearly completed its rotation the lug 172 will engage the arm 166 and move it to the position shown in Fig. 5, thereby moving block 168 to the right. Referring now to Fig. 14, it will be seen that 10 the upper right hand corner of the block 168 has engaged the frame (its right hand end) 35. It will also be seen that the pin 173, carried by the block 168, has engaged an inclined lug 174 carried by the pawl 58 and, 15 by lifting the pawl out of engagement with the rack-bar, permitted the conveyer to be moved by the block to the right. A pawl 175 carried by the block 168 hooks behind the frame 35 and, upon the return stroke of 20 the lever 166, draws the conveyer to its normal position. It is manifest that the arm 166 is not actuated by the lug 172 until after the gear 164 has made nearly an entire revolution. Therefore the return of the 25 conveyer occurs at the latter end of the return stroke of the operating handle. The movement of the link 167 is somewhat greater than is required to return the conveyer to its normal position, which enables the link to 30 carry the conveyer to a sufficient distance notwithstanding the spring 170 yields at the beginning of the return movement of the link 167 and the block 168 does not begin to move the conveyer home until the end of the 35 slot in the link engages the pin by which it is attached to the block.

An arm 176 is rigidly attached to rock shaft 42, outside of the frame; the first time a key is actuated after the conveyer has been 40 returned to its normal position this arm pushes down the free end of the pawl 175 and disengages it from the frame 35. The block 168, thereby released from the frame, is drawn to the left by the spring 170 a sufficient 45 distance to withdraw the pin 173 from engagement with the lug 174 and permit the pawl 58 to engage the rack-bar. The movement of the block also prevents the reengagement of the pawl 175 with the frame 35 after 50 the key is released.

A pawl 177 (Figs. 29, 30) carried by a depending lug 178 on the frame 35, actuated by a spring 179, is thrown under the rear end of the lever 120 when said lever is 55 rocked by the Fig. key, thereby holding the arm 112 in place between two plates 98. The pawl 177 has a depending tail 180 which, when the conveyer reaches its extreme right hand position, engages a pin 60 181 carried by side frame 27. Figs. 29 and 30 show the two positions of the parts referred to, the former figure showing the lever 120 held up by the pawl 177, the latter figure showing its relative position after being released by the pin 181.

Referring to Figs. 15 and 16 it will be seen that the upper edge of the member of the frame 35, having notch 116, has two levels; the higher level extending to the right from the notch and the lower to the 70 left. It is obvious that the position of the arm 115 with reference to the notch 116 at the time the conveyer reaches its extreme right hand position is variable, but in all cases it is at the left of notch 116. As the 75 conveyer moves to its normal position, the arm 112 having been disengaged from the carriage, the arm 115 lies on the lower level of the frame 35 and when the notch 116, during the movement of the conveyer to the 80 left, arrives beneath the arm 115 the arm falls into the notch, from which time the propeller is carried with the conveyer and returned to its normal position. The object of having the portion of the frame to the 85 right of the notch higher than that to the left is to insure the arm 115 falling into the notch even though the conveyer were moving rapidly. The horizontal link 182 is rigidly attached to the carriage 97; this link 90 has a slot and pin connection with the block 156 which permits the arm 153 and the block to move to the right independently of the carriage. When, upon the return stroke of the arm 153, the pin engages the 95 end of the slot in the link 182 it moves the carriage to its normal position. (See Figs. 1, 2, 3.)

The type segments 135 lie between a pair of inner side frames 190 (Figs. 1 and 42) 100 through which the shafts 125 and 130 pass. Rigidly secured to the latter shaft, between and close to each of said frames, is a segmental arm 191, adjacent to each of which is an arm 192 having a tongue 193 passing through a transverse slot in the shaft 130. A spring 194, attached to the shaft 125 in the same manner as springs 131, is hooked to the end of the tongue. The arm 191 has two ears, 195 and 196, which are adapted to engage a pin 197 and move the arm 192 in the direction in which it is moving. A pawl 198 carried by arm 191, has an oblique face 199 which, when the pawl is compelled to do so by a segmental guide 200, engages the 110 pin 197 and holds it against the ear 196. Referring to Fig. 42, which is a view looking toward the left hand plate 190 from the right hand side thereof, it will be seen that should the shaft 130 rotate clockwise, the 115 face 199 of the pawl being behind the pin 197 and the pawl being prevented from swinging toward the shaft by the guide 200, the arm 192 will be moved by the arm 191.

A member, to be hereinafter called the restorer, comprising a strip of metal with two inwardly turned lugs, 201 and 202, at each end is carried by the levers 192, the lugs 201 being pivotally attached to the extremities thereof. One end of a link 203 is pivotally 120 125 attached to the lever 192 and the other end is pivotally attached to the member 204. The member 204 is pivotally attached to the side frame 27. The member 204 is 130

attached to each lug 202; the free ends of the links carry hollow pins 204, which lie in a slot 205 formed in the arm 192. A loose fitting friction peg 206, preferably 5 wood or fiber, passes through each hollow pin and is confined between the face of the plate 190 and a segmental spring 207, the pressure of the spring being of sufficient strength to hold the peg immovable until 10 the rear end of the slot in the arm 192 engages the pin 204. Comparison of the position of the restorer shown in full lines in Fig. 42, which is in its normal position, with its position shown at A in dotted lines, 15 shows that the movement of the pin 204 in the slot has lifted the edge of the restorer to a point where it will pass the projected stops 103 without touching them.

When the arm 191 arrives at where the 20 end of the pawl 198 passes beyond the end of the guide 200, assuming that the friction of the peg is too great to be overcome by the spring 194, the pawl will be cammed inward as is being done in Fig. 43, thereby permitting 25 the arm 192 to stop while the arm 191 continues moving. The position of the ear 195 is such that just before the arm 191 reaches the end of its movement it engages the pin 197 and moves the arm 192 a short 30 distance farther, the object being to give the pawl plenty of room to resume its position behind the pin 197 on the return stroke, as is illustrated in Fig. 44. A pin 208 keeps the movements of the pawl within bounds, 35 while a pin 209 limits the movement of the arm 192.

Upon the return stroke of the arm 191 the ear 196 engages the pin 197 and moves the arm 192 with it. The position of the pin 40 204 now becomes reversed; i. e., the friction peg remains stationary until the pin is engaged by the rear end of the slot, thereby placing the restorer in the position shown in dotted lines at B, Fig. 42. Returning 45 home in this position it cams the projected stops 103 down to their normal positions; while so employed the position of the links 203 being radial the action upon the stops is positive and it does not depend upon the 50 friction of the pegs 206.

A pair of arms 210 is mounted to rock on shaft 95 and carry at their free ends a rock shaft 211 upon which is rotatably mounted a member I will hereinafter call 55 the platen. The platen is composed of a member 212 rigidly secured to the rock shaft 211, a series of sectors 213 preferably formed integrally with the member 212, and the impression bars 214 supported by 60 the sectors. (See Figs. 2, 3, 34, 35, 36, 37.) A pair of arms 215 is rigidly secured to the shaft 128; these arms are connected to links 216, which carry at their upper ends a rod 217. (See Figs. 1, 2, 3.) The rod 217 65 passes through the free ends of a pair of arms 218; the other ends of the two levers are mounted to rotate on the shaft 125. The arms 218 have slots of irregular shape, the three parts of which are designated by 219, 220 and 221. Rollers 222 mounted on 70 the rock shaft 211 roll in aforesaid slots. At the left hand end of the platen a lever 223 (Figs. 40 and 41) is pivotally mounted upon the inner side frame 190 and is normally drawn toward the rock shaft 211 by 75 a spring 224. Pins 225 and 226 driven into the left hand segment 213 are engaged by a hook 227 on the lever 223. This is illustrated in Fig. 40; in this figure the platen is shown by full lines in its normal position; i. e., the position it occupies when the operating handle is in its normal position, while in dotted lines the platen is shown with the first one of the impression bars 214 in contact with the type segments. In this 80 part of the figure the hook 227 has ridden over the pin 225 and as the platen returns to its normal position it engages the pin and rotates the platen a sufficient distance to bring the second impression bar 214 into 85 contact with the type segments at the next operation of the machine. A spring pressed frictional block 228 bears against the side of the first segment 213 and tends to hold the platen in position. A segment 230 (see 90 Figs. 34, 35, 36 and 37) is rigidly secured to the rock shaft 211 and has on its periphery three notches 231. The radius of the remainder of the periphery is shorter than that of the notched portion. A pin 95 233 carried by the sector is adapted to engage the edge of a lever 234. The edge thus engaged is eccentric with reference to the shaft 211. When a check is to be inserted the operator lifts the lever 223 and rocks 100 the platen toward him, knurled knobs being secured to the ends of the shaft 211 for this purpose. In Fig. 34 the platen is supposed to be moving toward the operator and in doing so it will, by the action of the pin 105 233 upon eccentric edge of lever 234, move the lever 235 which is mounted to rock upon the shaft 95 into the position it occupies in Fig. 37. When a check has been inserted the platen is rotated away from the 110 operator until the projection 232, which is in fact a division between two notches 231, engages a lug 239 on the lever 235, and when so stopped the platen is in the proper position to bring the first impression bar 115 214 in contact with the printing type segments. An arm 236 mounted on the shaft 95 and rigidly secured to lever 235 carries at its upper end frictional member 237, which is adapted to slide between the side frame 190 120 and the yielding plate 238 whereby the movements of the lever 235 are frictionally retarded.

A pawl 240 is carried by the right hand arm 218 and as the arm rises this pawl en- 125 130

gages a pin 241 carried by the lever 235 and cams the lever 235 toward the platen, causing the lug 239 to enter the notch 231 it then faces. This positively holds the platen 5 in proper alinement while a line is being printed. After a line is printed, as the platen begins to move away from the type segments the frictional member 237 holds the lever 235 stationary and thereby with- 10 draws the lug 239 from the notch 231. A pin 242 carried by the arm 210 moves in a slot 243 formed in the lever 235; the length of the slot is such that after the lug 239 has been withdrawn from the notch the pin 15 engages the end of the slot and carries the lever 235 with it. It will be seen that the early withdrawal of the lug 239 is necessary in order to enable the hook 227 to rotate the platen as has been described. The pawl 20 240 is arranged to rock and move out of the way of the pin 241 upon the downward stroke of the arm 218; this is illustrated in Fig. 39.

Fig. 50 shows a portion of a type segment and Fig. 51 a transverse section of a type segment and a longitudinal section of an impression bar. The face of the impression bar is serrated and the faces of the type are complementarily serrated.

When the shaft 128 is rocked by the operating handle the arms 215 move with the shaft and acting through links 216 lift the free ends of the arms 218. The part 219 of the slots is radial and the lifting of the 35 arms accomplishes nothing until the rollers arrive at the beginning of the part 220; then with a comparatively short upward movement of the arms 218 the platen is swung on the arms 210 to a point where 40 one of the impression bars 214 is quite close to the type segments 135. The rollers 222 then enter the last part, 221, of the slot which is so formed that a short movement of the platen is effected with a comparatively long movement of the arms 218 thereby the pressure necessary for printing a line is derived.

Two levers 245 are mounted to rotate upon the shaft 125, one of the levers being 50 outside of each of the inner side frames. The aperture through which the shaft passes is a slot placed approximately parallel with the lever. (See Figs. 4, 6, 47.) The free ends of the levers carry an inking roller 246. A link 247 is connected to each 55 of the levers 245 at a point somewhat above a line drawn from the ink roller to the shaft 125, and each of these links is attached to the rock shaft 211. An arm 248 extending in 60 a line approximately perpendicular to the lever 245 from a point opposite the shaft 125 forms together with the lever 245 a bell crank. A peg 249 formed of some frictional substance is gripped between a pair 65 of flat springs 250 and retards the move-

ment of the arm 248. Referring to the portion of Fig. 46 shown with full lines it will be seen that the platen is in normal position, the ink roller is away from the type segments and the shaft 125 is in the 70 right hand end of the slot. While the platen was moving from the position shown in full lines to that shown in dotted lines the bell crank pivoted on the peg 249 brought the ink roller into contact with the 75 type segment and the opposite end of the slot in contact with the shaft 125. Continued movement of the platen toward the type segments will now cause the bell crank to rotate upon the shaft 125 and the ink roller to roll across the faces of the type. Fig. 47 shows the position of the ink roller at the time the printing impression takes place. When the platen starts away from the type segments the bell crank again pivots on the peg 249 until the end of the slot engages the shaft 125, moving the ink roller away from the type, after which as the platen assumes its normal position the bell 80 crank rotates on the shaft and restores the ink roller to position shown in full lines in Fig. 46. A link 251 is attached to the lower end of each arm 248 and slides in a housing 252. The ends of the links, being beveled, engage the plungers 253 mounted 85 in the side plates 190 and cam them toward 90 the type segments.

When an impression is made upon the check the serrations on the type disrupt the paper and form a succession of fissures in the paper having the form of the character the type represents. The disruption of the paper increases its porosity and affords opportunity for absorption of ink from the faces of the type. The action of the links 100 251 is so timed that the plungers 253 are moved after the type segments to be employed have been selected and the remainder have come to a stop and the object of the plungers is to reduce the space occupied 105 by the sectors to the proper dimensions, thereby insuring registration of the serrations on the type with those on the impression bar.

Each type sector 135 carries a segment 115 260 (see Figs. 1, 31 and 32); diametrically opposite each of its type a type representing the same character is carried by the segment. Therefore, when the selected sectors are in position for printing a check a line of 120 type diametrically opposite is ready to print the same matter upon the record sheet. The record sheet is mounted upon a carrier comprising uprights 262 and 263 and tie rods 264 and 265. The carrier is mounted to 125 slide upon a rock-shaft 261, said shaft being supported by the side frames 26 and 27, and is moved along said shaft by a lever 266 pivoted at 267 (see Fig. 1) to the base 25, which is connected by a link 268 to the 130

lower end of the upright 263. (See Fig. 7.) The other end of the lever is located under the key board and has a suitable knob with which to move it. A bar 269, carried by the uprights, has a groove in which a strip 270 of rubber or other suitable material is cured and acts as a platen. A roller 271 is journaled in the uprights and has a ratchet wheel 272 rigidly secured to its shaft outside of the upright 263. An arm 273 swung on the shaft is moved in one direction by a spring 274; a spring pressed pawl carried by the arm engages the teeth of the ratchet wheel and rotates the roller 271 when the arm moves in opposition to the spring 274. A holding pawl 275 prevents backward movement of the roller. A roll of paper is mounted upon a rod lying in notches cut in the uprights; its end is drawn over the platen and attached to the roller 271. An ink ribbon 276 (see Fig. 52) passes in close proximity to the paper as it passes over the platen; the ends of the ribbon pass over the edges of the uprights, through slots 277 and are wound upon drums 278. (See Fig. 3.) These drums may be actuated by any suitable mechanism.

Arms 280, rigidly secured to and near each end of the shaft 261, just inside of the side frames 26 and 27, carry a rod 281 at their upper ends; this rod passes through the uprights 262 and 263. (See Figs. 1, 3, 33, 52.) One end of a link 282 is attached to each end of this rod, and a radial slot 283 in the other end of each link receives and is connected by a rivet 284 to sector 285 rigidly secured to each end of the rock shaft 128. The following parts being identical at both ends of the machine one set only will be described: A bell-crank 286 is pivotally attached to the side frame 26 and one of its arms is connected to the sector 285 by a link 287 by a slot and pin connection; the other arm has a hook 288 which engages a lug 289 on the link 282. A tension spring 290, connected to the sector 285 and link 282, is normally relaxed (see Fig. 52), but when the shaft 128 is rotated by the operating handle the spring is expanded as in Fig. 33; at the proper time (when the type segments 260 have come to rest) the link 287, moved by the sector 285, rocks the bell crank and disengages the hook 288 from the lug. Propelled by the springs 290 the record carrier is rocked and the platen 270 made to strike the type, thereby printing a record of what has just been printed on the check. Upon the return stroke the rivet 284 engages the end of the radial slot and rocks the carrier toward the back plate; the arm 273 engages the bar 291 on the back plate as the carrier moves, and rotates the roller 271. When the impression is made the upper rod 265 strikes flat springs 292 carried by the inner side frames 190, which though flexible enough to yield and permit the platen to strike the type, immediately move the platen away far enough to prevent the returning segments touching the ribbon. The record paper may be divided into vertical columns; by means of the lever 266 the carrier may be moved laterally on the shaft 261 and rod 281 and each record printed in any desired column.

The check is clamped to the platen by a pair of flexible strips 300, which are secured to the outside sectors 213 and are joined by two strips 301. (See Figs. 21 and 22.) The ends of the former are bent into suitable form and, having holes for the purpose, snap over pins 302 in the sectors. Releasing the strips permits them to spring up as shown in dotted lines in Fig. 22 to insert the check.

Having inserted the blank check and rolled the platen into position against the stop the keys are actuated as in a type writer. Actuating either of the keys marked "Space" presses down the rod 45 and shifts the conveyer one space. Aside from the fact of the keyboard moving, the thing which would first attract the attention of a typist is the absence of noise when the keys are actuated. A very important feature of my machine is the manner of correcting an error; it may almost be said that errors can be corrected before they are made. A typist seldom has to see what he has written to discover a mistake; he generally knows he has made a mistake the moment he strikes a key; but even then it is too late: the mistake is on the paper. When the operator strikes the wrong key in my machine, he can correct the error in this way: he presses the figure key, if it has not been pressed, presses and holds down the key at the extreme right of the keyboard marked "Shift" and pushes the conveyer to its extreme right hand position. He then moves the operating handle until the type segment not arrested by stops strike the rod 305 carried by the inner side frames 190; returning the handle to its normal position restores the stops 103; the conveyer is then moved manually to its left hand position, using the shift key to release the conveyer from the rack-bar. The manner of releasing the conveyer by pressing the shift key will be understood by reference to Fig. 1, where its inner end is seen to be under the pin 306 carried by the pawl 58. As the key rocks on the pin 307 its inner end lifts the pawl when the key is pressed down. The movement of the operating handle having been insufficient to move the platen or trip the record printing mechanism, the operator begins again from the beginning of the line he was setting up when the mistake occurred.

A blank sector 308 divides the letter from the numeral sectors. Although Fig. 50 is the only view showing the type on the sec-

tors 135, Fig. 3 shows the type on a few record segments 260. It is to be understood that all the sectors and segments on the right of sector 308 will have numerals and all to the left of the sector 308 will have letters. When the parts are all in normal position the first bank of stops is opposite the first type sector. When the propeller reaches its extreme right hand position the lever 112 is opposite the blank sector; since the propeller is in this position at the time the impression is made, and since when the Fig. key is pressed the lever 112 couples to the stop carriage, it follows that all the projected stops to the left of the lever 112 will arrest letter segments while those to the right will arrest numeral segments. Actuating a space key does not project a stop but it moves the conveyer one step. Therefore the sectors which happen to be in line with banks containing no projected stops travel with the shaft 125 until they strike the rod 305. Reference to Fig. 81 shows that the last type on the sector in the foreground has passed beyond the impression bar 214 while the last one on the segment 260 it carries has passed beyond the platen 270, from which it is clear that spaces in the printed line are the result of allowing certain sectors to make a full stroke.

Each of the sectors and segments has a type for printing a star (see Fig. 3), the use of which is illustrated in the following specimen line:

35 * John Smith \$100—00 *

Obviously no new figures could be added to those printed, both because the dollar sign has been used and because there is but a single space between the name and the amount. This space was caused by the Fig. key being used. In the following specimen line:

40 *One hundred & *— 100

45 the star is used to indicate there are no cents to be paid. The date may be written:

5—22—1912

In printing the three specimen lines shown the blank sector would be between II and \$ in the first line, between & and * in the second, and before 5 in the third; which is due to the fact that the lever 112 faces the blank sector at the time an impression is made. This, however, could be changed by altering the length of stroke of the propeller.

50 It is customary to provide a space wherein to write the figures indicating the amount of a check. Assuming the blank checks used in my machine have such a space and that the name of the payee is to appear on the same line, it is clear that if there is to be but a single space between the name and the amount, as in the first specimen line shown

above, the last letter of the name would have to be in the same place on each check. To do this with an ordinary typewriter it would be necessary, before starting, to determine the number of letters and spaces 70 there are in the name and print the first letter of the name a corresponding number of spaces to the left of the point where the name is to terminate. This would be entirely impracticable, and with my machine 75 it is not necessary. The operator begins just as though the first letter of the name is to be at the extreme left hand end of the name space. Having set up the name, he presses the Fig. key and proceeds to set up 80 the amount, giving no thought to the number of letters in the name. Notwithstanding this, when the printing is done the name 85 will be at the extreme left end of the amount space. Therefore, the name is always on one side and the amount on the other side of a given point on the check, said point being the division between the name and amount spaces. In like manner the operator would proceed to set up the 90 second specimen line shown, without regard for its length, and when printed the space between & and * would correspond with the division between the spaces provided for dollars and fractional parts of a dollar. 95

From the foregoing it is clear that with my machine a portion of a line may be printed on one side and the remainder of the line on the other side of a given fixed point, while the proportion of the line 100 which shall be on each side of said point is optional, and not necessarily predetermined.

Moreover, it is clear that the mechanism I have described could be used in connection with printing sectors of one sort; i.e., 105 all letter or all numeral sectors. In other words, by simply replacing the numeral by letter sectors, or replacing the letter by numeral sectors, the operator could print a line of numerals or letters and, within the 110 limits of the machine, have as much of the line printed on one side of the lever 112 as he pleases. There being too many ways in which this might be useful for me to attempt to enumerate them, I will point out 115 one: By putting two colors of ink on the inking roll 246, the line of division being coincident with the lever 112, part of a line could be printed in one color and the remainder in another. By using a two-color 120 ribbon the same thing could be done with the record.

It is more convenient to have the Fig. key move the conveyer one stop to the right each time it is actuated, because the space 125 between the name and amount is thereby made without using the space key. If desired, the same effect, but without moving the conveyer, may be obtained by pushing the lever 112 into a space between two plates 130

98. By this means, assuming the sector 308 were provided with numerals, (as it is in other respects the same as the other sectors) the space between the name and amount 5 could be eliminated. The lever 112 would in this case face the right hand letter sector, and the fixed point above referred to would be between said sector and the first numeral sector.

10 10 A lock 310 (see principally Figs. 33, 53, 54 and 55) is secured to frame 27 and its bolt is adapted to enter between two teeth of the segmental gear 127 and lock it against rotation. When so locked the machine is inoperative. In Figs. 55 and 56 the record sheet and duplicate printing parts are inclosed in a casing 311. A hinged back 312 and lid 313 are secured by a lock 314. When so inclosed the machine may be operated, checks printed and records thereof made, while the operator is debarred from access to the record.

15 25 I do not wish to be understood as confining my invention or its uses within the limits shown or described as numerous modifications might be made without departing from or exceeding the scope of my claims.

What I claim is as follows:

30 1. In a printing machine manually actuated keys mounted upon a conveyer, movable type carriers, means for moving said carriers their maximum distances each time the machine is operated, mechanism actuated by the keys and thereby prepared to stop the carriers before they have moved their maximum distances, and means for moving the conveyer with reference to said mechanism each time a key is operated so that at each operation of a key said mechanism is prepared to stop an additional carrier.

40 45 2. A printing machine having a plurality of manually actuated keys mounted upon a conveyer, means for moving the conveyer each time a key is actuated, a plurality of movable type carriers, means actuated by the keys for selecting the carriers to be used and means independent of the keys and of the selecting means for moving the carriers.

50 55 3. A printing machine having a plurality of manually actuated keys mounted upon a conveyer, means for moving the conveyer each time a key is actuated, a plurality of movable type-carriers each carrying a plurality of type, means actuated by the keys for selecting the type to be used, and means independent of the keys and of the selecting means for moving the type-carriers.

60 65 4. A printing machine having a plurality of operable elements, means which normally operate said elements in a specific manner, mechanism capable of various preparation and thereby enabled to cause variation in the operation of said elements,

manually operated keys mounted upon a conveyer and adapted to prepare said mechanism to perform its function, and means for moving the conveyer each time a key is operated so that at each operation of 70 a key said mechanism is prepared to affect the operation of a different one of said elements.

5 5 A printing device having a plurality of type carriers, each carrying a plurality 75 of characters, means for moving the carriers, selecting mechanism, means for setting the selecting mechanism and enabling it to stop the carriers when characters required to print a given line have come into 80 printing position, means for causing said mechanism to utilize carriers on one side of and adjacent to a space between two given carriers for the first portion of the line, and carriers on the other side of and adjacent 85 to said space for the remainder of the line.

6 6 A printing device having a plurality of type carriers, each carrying a plurality 90 of characters, selecting mechanism, means for setting the selecting mechanism and enabling it to stop the carriers when characters required to print a given line have come into printing position, means which may be operated after the setting mechanism has been set for a portion of said line for causing the mechanism to utilize carriers on one 95 side of and adjacent to a space between two given carriers for the portion of the line already set, and carriers on the other side of and adjacent to said space for the remainder 100 of the line.

7 7 A printing device having a plurality of type carriers, each carrying a plurality 105 of characters, means for moving the carriers, selecting mechanism, means for setting the selecting mechanism and enabling it to stop the carriers when characters required to print a given line have come into printing position, means for causing said mechanism to utilize carriers on one side of and adjacent 110 to a space between two given carriers for the first portion of the line, and carriers on the other side of and adjacent to said space for the remainder of the line, said means being available for use after the selecting 115 mechanism has been set for all characters required in the first portion of the line, whether the number of characters required in said first portion has been predetermined or not.

8 8 In a printing device, a plurality of movable type carriers, each carrying a plurality of characters, and means for moving the carriers; a selecting device for each carrier whereby said moving means may be 120 controlled and the carrier stopped with a predetermined character in printing position, a plurality of manually actuated keys whereby the selecting devices are set, said 125 keys being in operative position with refer- 130

ence to but one of said devices at a time, and means for moving the keys successively into similar operative position with reference to each of said devices.

5. In a printing device, in combination: a plurality of movable type carriers, each carrying a plurality of characters, a platen, and means for moving the carriers; a bank of movable stops for each carrier, each stop being adapted to stop the carrier with one of its characters in printing position, a plurality of manually actuated keys adapted to move the stops and enable them to stop the carriers, said keys being in operative relation with but one bank of stops at a time, and means for moving the keys into operative relation with the several banks successively.

10. In a printing device, in combination: a plurality of movable type carriers, each carrying a plurality of characters, a platen, and means for moving the carriers; a bank of movable stops for each carrier, each stop being adapted to stop the carrier with one of its characters in printing position, a conveyor bearing a plurality of manually actuated keys, each key being adapted to move one stop of a bank and enable it to stop the carrier, and means for moving the conveyor step by step to bring the keys into operative relation with the several banks successively.

15. In a printing device, in combination: a plurality of movable type carriers, each carrying a plurality of characters, a platen, and means for moving the carriers; a bank of movable stops for each carrier, each stop being adapted to stop the carrier with one of its characters in printing position, a conveyor bearing a plurality of manually actuated keys, each key being adapted to move one stop of a bank and enable it to stop the carrier, and mechanism whereby the conveyor is moved and the keys brought into operative relation with the next adjacent bank as each key is released and allowed to return to normal position.

20. In a printing device, in combination: a plurality of movable type carriers, each carrying a plurality of characters, and means for moving the carriers; a carriage carrying a plurality of movable stops arranged in banks, the stops of each bank being adapted to stop one carrier; means for moving a stop in each of one or more banks into position for stopping a carrier, and means for moving the carriage into position where the stops which have been set will engage and stop certain type carriers.

25. In a printing device, in combination: a plurality of movable type carriers, each carrying a plurality of characters, and means for moving the carriers; a carriage carrying a plurality of movable stops arranged in banks, the stops of each bank be-

ing adapted to stop one carrier; a plurality of manually actuated keys by which the stops may be moved and set so they will stop the carriers, and means for moving the carriage into position where the stops which have been set will engage and stop certain type carriers.

30. In a printing device, a plurality of movable type carriers, each carrying a plurality of characters, and means for moving the carriers; a carriage carrying a plurality of movable stops arranged in banks, ~~said~~ carriage being normally in position where each bank is in operative position with reference to one carrier, means for setting a stop in each bank beginning with the first, so each stop set will be enabled to stop a carrier, means for moving the carriage after the stops have been set, moving it in the direction corresponding to the order in which the stops were set, and means for limiting the movement of the carriage to a distance inversely proportional to the number of stops which have been set.

35. In a printing device having a plurality of type to select from and means for selecting the ones to be used in printing a given impression, in combination: a selecting mechanism mounted upon a carriage, a plurality of keys for setting the selecting mechanism so it will bring the desired type into action, and a propeller for but normally detached from the carriage, means for attaching the propeller to the carriage, and means for moving the propeller, whereby to bring the carriage into position where the selecting mechanism can select the required type.

40. In a printing device having a plurality of type to select from and means for selecting the ones to be used in printing a given impression, in combination: a selecting mechanism mounted upon a carriage, a plurality of keys for setting the selecting mechanism so it will bring the desired type into action, and a propeller for but normally detached from the carriage; means for moving the propeller a given distance each time a key is actuated, means for attaching the propeller to the carriage after a desired number of keys have been actuated, and means independent of the keys for moving the propeller without actuating a key, whereby the carriage may be moved and the selecting mechanism placed in position for selecting the type.

45. In a printing device having a plurality of type to select from and means for selecting the ones to be used in printing a given impression, in combination: selecting mechanism mounted upon a carriage, a plurality of keys for setting the selecting mechanism so it will bring the desired type into action, and a propeller for but normally detached from the carriage; means for mov-

- ing the propeller a given distance each time a key is actuated, means for attaching the propeller to the carriage after the selecting mechanism has been set, and means, independent of the keys, for moving the propeller after it is attached to the carriage whereby to bring the carriage into position where the selecting mechanism can select the required type. 70
18. In a printing device having a plurality of type to select from and means for selecting the ones to be used in printing a given impression, in combination: a selecting mechanism mounted upon a carriage, 75 said carriage having a succession of recesses, a plurality of keys for setting the selecting mechanism so it will select the desired type, and a propeller having a pawl adapted to enter the aforesaid recesses, the normal position of the pawl being opposite the first recess, said propeller having a limited stroke; means for moving the propeller a given distance, each time a key is actuated, causing the pawl to face the recesses successively, means for throwing the pawl into any recess it faces, and means, independent of the keys, for moving the propeller the remainder of its stroke and taking the carriage with it. 80
19. In a printing device having a plurality of type to select from and means for selecting the ones to be used in printing a given impression, in combination: a selecting mechanism mounted upon a carriage, 85 said carriage having a succession of recesses, a plurality of keys for setting the selecting mechanism so it will select the desired type, and a propeller having a pawl adapted to engage one of the aforesaid recesses, the normal position of the pawl being opposite the first recess; means for moving the propeller a given distance each time a key is actuated, causing the pawl to face the recesses successively, means for throwing the pawl into a recess, means whereby keys may be actuated after the pawl is thrown into a recess without the propeller being moved, and means, independent of the keys, for moving the propeller. 90
20. In a printing device having a plurality of type to select from and means for selecting the ones to be used in printing a given impression, in combination: a selecting mechanism mounted upon a carriage, a conveyer bearing a plurality of keys, said conveyer being normally in position to enable the keys to act upon part of the selecting mechanism, and means for moving the conveyer a given distance each time a key is actuated, bringing the keys into operative relation with a new part of the selecting mechanism at each movement; a propeller normally connected to and moved by the conveyer, means for detaching the propeller from the conveyer and attaching it to the carriage, and means, independent of the keys, for moving the propeller, whereby to bring the carriage into position where the selecting mechanism can select the required type. 95
21. In a printing device having a plurality of type to select from and means for selecting the ones to be used in printing a given impression, in combination: a selecting mechanism mounted upon a carriage, 100 said carriage having a succession of recesses, a conveyer bearing a plurality of keys, said conveyer being normally in position to enable the keys to act upon part of the selecting mechanism, and means for moving the conveyer a given distance each time a key is actuated, bringing the keys into operative relation with a different part of the selecting mechanism at each movement; a propeller having a pawl adapted to enter the aforesaid recesses or enter a single recess formed in the conveyer, the normal position of the pawl being in the latter recess and facing the first of the carriage recesses; means for removing the pawl from said recess and throwing it into the carriage recess it faces at the time, and means for moving the propeller the remainder of its stroke carrying the carriage with it. 105
22. In a printing device in combination: a plurality of movable type carriers, each carrying a plurality of characters, a platen, and means for moving the carrier; a carriage carrying a plurality of movable stops arranged in banks, the stops of each bank 110 being adapted to stop a carrier, and a conveyer bearing a plurality of keys, each key normally adapted to engage and move a particular stop of the first bank into the path of a carrier; a succession of recesses formed in the carriage, a single recess formed in the conveyer, and a propeller having a pawl which normally lies in the latter recess while facing the first of the former recesses; means for moving the conveyer each time a key is actuated and bringing the keys into operative relation to the several banks successively, means for removing the pawl from the single recess and placing it in the recess it faces, and means 115 for moving the propeller, and through it the carriage, a distance inversely proportional to the number of times a key had been actuated before the pawl was shifted. 120
23. In a printing device having a plurality of movable type carriers and means for moving them; a plurality of movable stops, a support therefor, means for moving the stops and projecting them into the paths of the carriers, and a restorer which 125 moves through the plane occupied by the projected portion of the stops in a direction different from that in which the stops move, said restorer being so constructed that it thrusts from its path all stops it engages. 130

24. In a printing device having a plurality of movable type carriers and means for moving them; a plurality of movable stops, a support therefor, means for moving the stops and projecting them into the paths of the carriers, a friction device for holding each stop where it is placed, and a restorer which moves through the plane occupied by the projected portion of the stops in a direction different from that in which the stops move, said restorer being so constructed that it thrusts from its path all stops it engages.
25. In a printing device having a plurality of movable type carriers, each carrying a plurality of characters, and means for moving the carriers, in combination: a plurality of movable stops, a support therefor, means for moving a stop into the path of each type carrier, a friction device for holding each stop where it is placed, a restorer comprising a device having an inclined face adapted to move in a line substantially perpendicular to the direction in which the stops move, said inclined face engaging and removing all stops from its path, thereby removing them from the paths of the carriers; and means for moving the restorer.
26. In a printing device having a plurality of movable type carriers, each carrying a plurality of characters, and means for moving the carriers, in combination: a plurality of movable stops, a support therefor, means for moving a stop into the path of each type carrier, means for holding each stop where it is placed, a restorer comprising a device having an inclined face adapted to move through the space traversed by the type carriers, its face engaging and removing all stops from the paths of the carriers, and means for moving the restorer.
27. A printing device having a plurality of movable type carriers, means for moving them into position where the type they carry may be used to print, said means, however, tending to move the carriers too far, and stops which may be projected into the paths of the carriers to stop them at the desired point; means for returning the carriers, and means for engaging the projected portion of the stops and restoring them to their normal positions, said means acting on the stops successively.
28. In a printing device having a plurality of movable type carriers, each carrying a plurality of characters, and means for moving the carriers, the following combination: a plurality of movable stops, a support therefor, means for projecting one or more of said stops into the paths of the carriers, and means for holding each stop where it is placed; a device which reciprocates in a direction substantially perpendicular to the direction of movement of the stops, moving in one direction in a plane removed from, and in the other direction in the plane occupied by the projected stops and which, having an inclined face to engage and move the stops, restores them to their normal positions; means for imparting reciprocating motion to said device and means for moving it from one plane to the other.
29. In a printing device having a plurality of movable type carriers, each carrying a plurality of characters, and means for moving the carriers, the following combination: a plurality of movable stops, a support therefor, means for projecting one or more of said stops into the paths of the carriers, and means for holding each stop where it is placed; a device which reciprocates in a direction substantially perpendicular to the direction of movement of the stops, moving in one direction in a plane removed from, and in the other direction in the plane occupied by the projected stops and which, having an inclined face to engage and move the stops, restores them to their normal positions; means for imparting reciprocating motion to said device, frictionally actuated means for moving it from one plane to the other, and means for holding it positively when in the plane of the stops.
30. In a printing device having a plurality of movable type carriers, each carrying a plurality of characters, and means for moving the carriers, the following combination: a plurality of movable stops, a support therefor, means for projecting one or more of said stops into the paths of the carriers, and means for holding each stop where it is placed; a restorer adapted to engage and restore all projected stops to their normal position, pivotally mounted upon a member which reciprocated in a direction substantially perpendicular to the movement of the stops, a link having one end pivotally attached to the restorer and having a pin at the other end sliding in a slot formed in the aforesaid member, said link, pin and slot being so situated and proportioned that when the pin is in one end of the slot the restorer is removed from the plane of the projected stops, and when it is in the other end of the slot the restorer is in the plane of the projected stops, and means for moving the pin to one end of the slot as soon as the aforesaid member starts to move in one direction and for moving it to the other end of the slot as soon as said member starts to move in the other direction.
31. In a printing device having a plurality of movable type carriers, each carrying a plurality of characters, and means for moving the carriers, the following combination: a plurality of movable stops, a support

- therefor, means for projecting one or more of said stops into the paths of the carriers, and means for holding each stop where it is placed; a restorer adapted to engage and restore all projected stops to their normal position, pivotally mounted upon a member which reciprocated in a direction substantially perpendicular to the movement of the stops, a link having one end pivotally attached to the restorer and having a pin at the other end sliding in a slot formed in the aforesaid member, said link, pin and slot being so situated and proportioned that when the pin is in one end of the slot the restorer is removed from the plane of the projected stops, and when it is in the other end of the slot the restorer is in the plane of the projected stops, said pin being tubular and having therein a loose fitting plug extending beyond both ends of the pin, and a pair of flat surfaces between which the plug is clamped with a yielding pressure. 80
- 5 34. In a printing device having a plurality of movable type carriers, means for moving them, and stops for stopping them the following combination: a plurality of said stops mounted in banks in a supporting device, each stop being housed in a recess and capable of longitudinal movement therein; a transverse hole drilled in each stop containing a compression spring, whose ends bearing against the sides of the recess, tend to keep the stop in whatever position it is placed. 85
- 10 35. In a printing device having a plurality of movable type carriers, means for moving them and stops for stopping them, the following combination: a plurality of said stops mounted in banks in a supporting device, each stop being housed and capable of limited longitudinal movement in a recess; a conveyer carrying a plurality of keys and a plurality of stop moving devices arranged in the order of and in operative relation with reference to one bank of stops, connecting means between each key and one of said devices, whereby when a key is actuated the device to which it is connected is made to engage and project a stop into the path of a carrier, and means for moving the conveyer each time a key is actuated and bringing the stop moving devices into operative relation with the next bank of stops. 90
- 15 36. In a printing device having a plurality of movable type carriers, means for moving them and stops for stopping them, the following combination: a plurality of said stops mounted in banks in a carriage, each bank being normally in operative position with reference to one type carrier, each stop being housed and capable of limited longitudinal movement in a recess; a conveyer carrying a plurality of keys and stop moving devices, the latter arranged in the order of and in operative relation with reference to one bank of stops, a connection between each stop moving device and a key whereby when the key is actuated the device is made to engage and project a stop into the path of a type carrier, means for moving the conveyer and bringing the devices into operative relation with reference to the next bank 100
- 20 32. In a printing device having a plurality of movable type carriers, each carrying a plurality of characters, and means for moving the carriers, the following combination: a plurality of movable stops, a support therefor, means for projecting one or more of said stops into the paths of the carriers, and means for holding each stop where it is placed; a restorer adapted to engage and restore all projected stops to their normal position, pivotally mounted upon a member which reciprocated in a direction substantially perpendicular to the movement of the stops, a link having one end pivotally attached to the restorer and having a pin at the other end sliding in a slot formed in the aforesaid member, said link, pin and slot being so situated and proportioned that when the pin is in one end of the slot the restorer is removed from the plane of the projected stops, and when it is in the other end of the slot the restorer is in the plane of the projected stops, said pin being tubular and having therein a loose fitting plug extending beyond both ends of the pin, and a pair of flat surfaces between which the plug is clamped with a yielding pressure. 95
- 25 33. In a printing device having a plurality of movable type carriers, each carrying a plurality of characters, and means for moving the carriers, the following combination: a plurality of movable stops, a support therefor, means for projecting one or more of said stops into the paths of the carriers, and means for holding each stop where it is placed; a restorer adapted to engage and restore all projected stops to their normal position, pivotally mounted upon a member which reciprocated in a direction substantially perpendicular to the movement of the stops, a link having one end pivotally attached to the restorer and having a pin at the other end sliding in a slot formed in the aforesaid member, said link, pin and slot being so situated and proportioned that when the pin is in one end of the slot the restorer is removed from the plane of the projected stops, and when it is in the other end of the slot the restorer is in the plane of the projected stops, said pin being tubular and having therein a loose fitting plug extending beyond both ends of the pin, and a pair of flat surfaces between which the plug is clamped with a yielding pressure. 105
- 30 40 45 50 55 60 65

of stops each time a key is moved, and means for moving the carriage a distance inversely proportional to the number of times a key has been operated, whereby the projected 5 stops will be in position to engage and stop other type carriers than those they would have engaged had the carriage not been moved.

37. In a printing device having a plurality 10 of movable type carriers, means for moving them and stops for stopping them, the following combination: a plurality of said stops mounted in banks in a carriage, each bank being normally in operative position with 15 reference to one type carrier, each stop being housed and capable of limited longitudinal movement in a recess; a conveyer carrying a plurality of keys and stop moving devices, the latter arranged in the order of and in 20 operative relation with reference to one bank of stops, a connection between each stop moving device and a key whereby when the key is actuated the device is made to engage and project a stop into the path of a type 25 carrier, means for moving the conveyer and bringing the devices into operative relation with reference to the next bank of stops each time a key is moved, and means for moving the carriage and bringing each projected 30 stop into the path of a type carrier a number of steps removed from its normal position inversely proportional to the times a key has been pressed.

38. In a key manipulated device having a 35 manually actuated key and mechanism to be thereby operated, the following combination: a tube, a flexible inelastic member capable of movement in the tube, means for imparting longitudinal movement to said 40 member by manipulation of the key, and means for transmitting said movement to the mechanism.

39. In a key manipulated device having a 45 manually actuated key and two or more independent mechanisms to be thereby operated, the following combination: a tube, a flexible member capable of movement in the tube, means for moving the member longitudinally in the tube by actuating the key, 50 means whereby when said flexible member moves in one direction in the tube it actuates one of said mechanisms, and means whereby said mechanisms will be operated successively by successive operations of the 55 key.

40. In a key manipulated device having a 60 manually actuated key and mechanism to be operated thereby, the following combination: a tube, supports in which the ends of 65 the tube are secured, a wire in the tube long enough to permit both of its ends to project beyond the ends of the tube, a terminal for each end having a hole to receive the protruding end of the wire but leaving a portion of the wire uninclosed by either the

tube or the terminals, thereby permitting longitudinal movement of the wire in the tube, guides to constantly support and prevent any but longitudinal movement of the terminals, and means whereby the key may 70 engage one of the terminals and move the wire in the tube.

41. In a key manipulated device having a manually actuated key and mechanism to be operated thereby, the following combination: 75 a tube, supports in which the ends of the tube are secured, a wire in the tube long enough to permit both of its ends to project beyond the ends of the tube, a terminal for each end having a hole to receive the 80 protruding end of the wire but leaving a portion of the wire uninclosed by either the tube or the terminals, thereby permitting longitudinal movement of the wire in the tube, guides to constantly support and prevent 85 any but longitudinal movement of the terminals, a spring which tends to move the wire and terminals in one direction in the tube, and means whereby the key may engage one of the terminals and move the wire 90 in the opposite direction to that in which it is moved by the spring.

42. In a printing device having a manually actuated key and mechanism remote from but to be moved by said key, means for 95 transmitting motion of the key to said mechanism, comprising: a flexible member confined in a curved tube, means whereby when the key is pressed the flexible member is pushed longitudinally in the tube, and a 100 spring at the end of the tube remote from the key, whereby the flexible member is pushed back when the key is released.

43. In a printing device having a manually actuated key and mechanism remote 105 from but to be moved by said key, means for transmitting motion of the key to said mechanism, comprising: a flexible member confined in a curved tube, means whereby when the key is pressed the flexible member 110 is pushed longitudinally in the tube, a spring at the end of the tube remote from the key, whereby the flexible member is pushed back when the key is released, and means whereby the remote end of the wire moves said mechanism. 115

44. In a key manipulated device having a plurality of banks of mechanisms, to be operated by the keys, the following combination: a conveyer carrying a plurality of 120 keys and tubes, each tube inclosing a wire, one end of each tube being supported in such position with reference to one of the keys that when the key is actuated the inclosed wire will be pushed longitudinally in 125 the tube; the other ends of the tubes being assembled in a group of such form and position that the wire in each tube is in operative position with reference to a mechanism in one of the aforesaid banks, and 130

means for moving the conveyer each time a key is actuated and bringing the group of tubes into like position with the several banks successively.

5 45. A printing device having a plurality of type carriers, a plurality of keys and mechanism associated therewith by which the type on two or more of said carriers may be brought into position to print simultaneously, said carriers being divided into groups, means whereby type which are thereby brought into printing position may be drawn from either group, or part of them may be drawn from each group, and means 10 whereby when said type are in printing position the division between those belonging to one group and those belonging to another is always located at a certain given point with reference to a fixed point on the printing device.

15 46. In a printing device, the combination of a plurality of independently movable type carriers, each carrying one or more type the faces of which are serrated, a platen 25 whose surface has serrations complementary to those on the faces of the type, means for moving the carriers and bringing two or more type contemporaneously opposite the platen, means for simultaneously pressing 30 said type and platen together, and means for insuring the registration of the serrations on the type with those on the platen.

40 47. In a printing device, the combination of a plurality of independently movable type carriers, each carrying one or more type the faces of which are serrated, a platen whose surface has serrations complementary to those on the faces of the type, all the serrations being parallel with the direction 45 of movement of the carriers, means for moving the carriers and bringing two or more type contemporaneously opposite the platen, means for simultaneously pressing the type and platen together, and means for insuring the registration of the serrations on the type with those on the platen.

48. In a printing device, the combination of a plurality of independently movable segments, each having one or more type on its 50 periphery the faces of said type being serrated, a platen whose surface has serrations complementary to those on the type faces, means for rotating the segments and bringing two or more type contemporaneously 55 opposite the platen, the platen being adapted to coact simultaneously with said plurality of type; and means for pressing the type and platen together, and means, in which the direction of the serrations is an element, 60 for insuring registration of the serrations on the platen with those on the several type.

49. In a printing device, the combination of a plurality of independently movable segments each having one or more type on its 65 periphery the faces of said type being ser-

rated, a platen whose surface has serrations complementary to those on the type faces, the serrations being parallel with the movement of the segments.

50. In a printing device, the combination 70 of a plurality of independently movable segments, each having one or more type on its periphery the faces of said type being serrated, a platen whose surface has serrations complementary to those on the type faces, 75 the faces of the type being arcual, and the face of the platen complementarily curved, the serrations being parallel with the movement of the segments.

51. A printing machine having a bank of 80 manually actuated keys mounted to rock upon a common axis and in position to operate certain mechanism, and means whereby each time a key is operated the whole bank is moved parallel with said axis to a 85 position where the keys can operate other mechanism.

52. A printing machine having manually operated keys mounted to rock upon a common axis, devices adapted to be operated by 90 the keys when they are in a certain position with reference thereto, said devices being arranged in groups, means for supporting the keys in position to operate the devices of one group, and means for moving them to another group each time a key is operated, the movement being parallel to said axis.

53. A printing machine having manually operated keys mounted to rock upon a common axis, mechanism adapted to be operated 100 by the keys when they are in a certain position with reference thereto, means for placing the keys in said position, and means for moving them to a similar position with reference to other mechanism when a key is operated, the movement being parallel to said axis.

54. In a printing device, a plurality of sectors mounted to rotate upon a hollow shaft, each sector carrying a plurality of type upon its periphery, a succession of parallel transverse slots in said shaft, through which tongues projecting inwardly from the sectors pass, a shaft within and arranged to rotate in unison with the hollow shaft, spiral 110 springs surrounding the inner shaft with their inner ends attached thereto, the outer end of each spring being attached to one of the tongues, and means for rotating said shafts.

55. In a printing device, a plurality of independently movable type carriers, each carrying a plurality of type, a shaft on which said carriers are rotatably mounted, stops adapted to be projected into the paths of 125 the carriers whereby they may be stopped when certain type on them have arrived at a predetermined point, means for rotating the shaft a fixed distance at each operation of the machine, and means for causing each 130

carrier to rotate in unison with the shaft until it is arrested by a stop,

56. In a printing device, a plurality of independently movable type carriers, each carrying a plurality of type, a shaft on which said carriers are rotatably mounted, stops adapted to be projected into the paths of the carriers whereby they may be stopped when certain type on them have arrived at 10 a predetermined point, means for rotating the shaft a fixed distance at each operation of the machine, and a yielding connection between the shaft and each carrier whereby it is made to rotate with the shaft until 15 arrested by a stop.

57. In a printing device, a plurality of independently movable type carriers, each carrying a plurality of type, a shaft on which said carriers are rotatably mounted, stops 20 adapted to be projected into the paths of the carriers whereby they may be stopped when certain type on them have arrived at a predetermined point, means for rotating the shaft a fixed distance at each operation 25 of the machine, and a spring connection between the shaft and each carrier whereby it is made to rotate with the shaft until arrested by a stop:

58. In a printing device, a plurality of independently movable type carriers, stops adapted to be projected into the paths of the carriers, a movable element, and means which causes each carrier to move in unison with said element until arrested by a stop.

59. A printing device having a plurality of type carriers, a plurality of keys and mechanism associated therewith by which the type on two or more of said carriers may be brought into position for printing 35 simultaneously, said carriers being divided into groups, the carriers of each group being adapted, when in operative relation therewith, to be operated by the keys and said associated mechanism; the carriers of 40 one group being normally in operative relation with reference to the keys, and a special key which, when actuated, causes discontinuance of said normal operative relation and establishment of similar relations between the keys and the other group.

60. A printing device having a plurality of type carriers, a plurality of keys and mechanism associated therewith by which the type on two or more of said carriers may 35 be brought into position for printing simultaneously, said carriers being divided into groups, the carriers of each group being adapted when in operative relation therewith to be operated by the keys and said associated mechanism; means for bringing the 40 keys and associated mechanism into operative relation with the carriers of either group, and symbols on each key each symbol

representing one of the characters which the key is adapted to bring into printing position.

61. In a printing device, a plurality of independently movable type carriers, each carrying a plurality of type, a platen, means for moving the carriers and causing the type thereon to pass the platen in succession, stops adapted to be projected into the paths of the carriers, whereby they may be stopped when desired type arrive opposite the platen, and means for actuating the platen to print 75 an impression with the type which have stopped opposite it.

62. In a printing device, a plurality of independently movable type carriers, each carrying a plurality of type, a movable member, a yielding connection between each type carrier and said member whereby they are caused to move in unison with said member, and stops adapted to be projected into the paths of the carriers, whereby two or more 85 carriers may be stopped with a required type on each in alignment with required type on all the other arrested carriers and thereby held while the aligned type are used for printing.

63. In a printing device, a plurality of independently movable type carriers, each carrying a plurality of type, a movable member, a yielding connection between each type carrier and said member, whereby they are 95 caused to move in unison therewith, stops adapted to be projected into the paths of the carriers, whereby any of the carriers may be stopped when selected type they carry arrive opposite a given fixed point, and 100 means for printing with the type which have been selected.

64. In a printing device, a plurality of juxtaposed movable type carriers and means for moving them, a carriage carrying a plurality of movable stops arranged in banks, said carriage being normally in position where each bank of stops is contiguous to a type carrier, means for setting the stops so they will be enabled to arrest the moving 110 type carriers, said means enabling one stop to be set in each of one or more banks, and means for moving the carriage after setting of the stops is completed so as to bring a given bank of stops into contiguity with 115 another type carrier than that to which it is normally contiguous, the number of type carriers intervening between the one said bank is normally contiguous to and the one to which is moved varying inversely with 120 the number of stops set.
